ROTARY LAWN SPRINKLER

James E. Ashworth, Oakland, Calif.

Application December 1, 1947, Serial No. 789,087

8 Claims. (Cl. 299—18)

1

This invention relates to a rotary lawn sprinkler and more particularly to a sprinkler designed to vary the pattern of the sprinkled area from a conventional circular outline.

It is the object of the present invention to provide a portable lawn sprinkler which is adapted to water a non-circular area with uniform spraying effects to attain most efficient utilization of the available water supply.

It is a further object of the invention to provide an automatically operating spraying device for patterned areas, which is rugged and economical in construction and which is positive and certain in its operation.

Another object of the invention is to provide a driving arrangement for a rotary lawn sprinkler which is independent of the amount of water which is discharged therefrom or the area which is sprinkled thereby. The drive is attained from a branch path of the water supply and serves to convert the kinetic energy of a small fluid stream operating a water wheel at high speed and low torque to a rotary movement of the sprinkler nozzle operating at low speed and high torque.

It is another object of the invention to provide a rotary nozzle with a flexible portion capable of assuming varying inclinations in the course of rotary travel of the nozzle, the tilting effects of which are attained with certainty by a novel leverage system which converts comparatively small displacements of a controlling element to the maximum desired inclinations of the discharge portion of the nozzle.

The invention proceeds upon the principle of providing a stationary upstanding cylindrical frame with a cam track on the upper edge thereof provided with a plurality of alternately displaced rises and depressions, which in the illustrated embodiment of the invention have been shown with four of such spaced 90° apart, to effect the spraying of a square area. A rotary nozzle embodying a flexible portion experiences tilting movements corresponding to these rises and depressions as the same is rotated so that the corners of the square area may be watered at the points of maximum nozzle inclination to the horizontal corresponding to the rises of the cam track, while the sides of the square area are watered during the travel of the nozzle guide on the lower portions of the cam track; and to attain a well delineated pattern the ascents and descents from the rises are comparatively steep.

The mechanical advantage of an interconnected lever system is utilized to obtain a positive action for the angular lowering and lifting movements of the nozzle. At the same time a positive rotary drive of the nozzle is attained by the use of a water wheel which is actuated by a separate jet of water branched off from the water supply, the rapid rotary movement of which

2

at high speed and low torque is transformed to a slow rotary movement of the nozzle at high torque through the intermediary of efficient reduction gearing. The jet of water for the drive of the water wheel may be controlled independently of the main supply of water to render the rotary drive for the nozzle adjustable and still independent of the amount of water discharged from the nozzle, the area watered thereby or the operating head of the water supply.

Other objects and purposes will appear from the detailed description of the invention following hereinafter, taken in conjunction with the accompanying drawings, wherein

Fig. 1 is a perspective view with certain portions broken away of the improved rotary sprinkler in accordance with the present invention;

Fig. 2 is a vertical sectional view of the sprinkler along line 2—2 of Fig. 3;

Fig. 3 is a horizontal sectional view along line 3—3 of Fig. 2;

Fig. 4 is a developed elevation of the cam track at the upper end of the cylindrical frame for controlling the inclination of the rotary nozzle; and

Fig. 5 is a perspective view of the pattern of the square area sprinkled by the improved sprinkler in accordance with the invention.

In Fig. 1 is shown the operative assembly of the rotary sprinkler which is formed by a main cylindrical frame 10 on the bottom of which may be threaded a supporting base therefor 11, which is shown of square configuration, but which may be varied to assume any other geometrical form such as round, hexagonal, etc. The base 11 increases the stability of the assembly which is set up on a lawn in the center of the area which is sought to be sprayed or watered.

A horizontal water supply pipe 12 extends through the vertical wall of the cylindrical frame housing 10 near the bottom thereof and a detachable coupling 14 is disposed at the free end thereof for connecting a hose, water pipe or other conduit 13 leading from a source of water, to the interior of the sprinkler. The supply pipe 12 extends inwardly of the frame 10 to the base 15 of the vertical water pipe shaft 16 which is shown threaded into the upper end of the base 15 at 17. The vertical water pipe shaft 16 is disposed along the exact central axis of the cylindrical frame 10 and acts as the center of rotation of the rotary nozzle frame 20 provided with an upstanding portion 21. The interior center portion of the nozzle frame 20 is packed with a compression spring 19, split gasket 18 and packing 17 to provide a packing area between the nozzle frame 20 and vertical pipe shaft 16 which is water tight, but which nevertheless operates with minimum rotary friction. The interior end portions and bottom horizontal surface of nozzle frame 20, as well as top horizontal surface

of base 15, is machine finished to provide a horizontal rotating surface with minimum rotary friction.

The upper portion 21 of the nozzle frame is of U-shaped cross-section to provide a guide for the flexible nozzle portion 40 which may be formed of corrugated metal, rubber, reenforced rubber or the like, and which is fastened within the upper end of nozzle frame 20 by soldering, threading or the like. The open lateral wall of the U-shaped frame 21 permits the flexible nozzle portion 40 to assume varying degrees of inclinations, and at the same time the walls of the U-shaped frame 21 provide connecting points for the leverage system for controlling the inclination of the nozzle frame, as is more fully explained hereinafter.

A rotary nozzle frame 20-21 is provided with a horizontal shelf 22 near the upper end thereof and spaced vertical wing 23, adjacent the lower end thereof, for mounting a vertical rotary shaft 26 which imparts rotary motion to the sprinkler. The wing 23, lying in a vertical plane, terminates in spaced cylindrical bearings 24 and 24', respectively, for the reception of the lower end of vertical shaft 26. A worm or endless screw 27 is mounted on vertical shaft 26 near the lower end thereof between bearings 24 and 24', forming one component of a worm gear unit at the center of the wing 23. An opening 25 in the horizontal shelf 22, extending laterally from the upper end of the nozzle frame 21, operates as another bearing point for the vertical shaft 26, on the upper end of which is mounted a water wheel 65 having a plurality of blades 62 which are adapted to be actuated by a jet of water issuing from the end 61 of branch pipe 60 which is connected to the vertical wall of the nozzle frame 20, through bore 64, at a point above the end of the fixed vertical water pipe 16. The bore 64, as well as pipe 60, are of small cross-sectional area so that maximum flow of water takes place therethrough for all variations of flow through the main sprinkler pipe 16, even when the same operates at its lowest output capacity. The end 61 of the pipe 60 is preferably flattened, and if desired, a valve 65 may be inserted in this branch pipe to control the force of the jet of water impinging upon the blades 62, to thereby control the speed of the water wheel or turbine.

A horizontal fixed shaft 29 extends transversely from the nozzle frame 20 to which it is rigidly connected and carries thereon a rotating sleeve 30 having an integral spiral toothed wheel 28 in meshing engagement with the worm 27 to operate as the spur-wheel or worm-wheel of the second component of a worm gear assembly. An integral pinion or gear wheel 31 is mounted at the opposite end of the sleeve 30 and is in engagement with a gear track 32 which is cut on the upper face of a ring 33 which is fastened on the inner wall of the frame 10 by any suitable means such as bolts or rivets 34. The horizontal rotary high-speed low-torque movement imparted to the water wheel 65 by the stream of water issuing from nozzle 61 is transmitted to worm 27 through vertical shaft 26, imparting medium-speed and medium-torque to worm wheel 28, and the integral pinion 31 rotating about fixed shaft 29 rigidly mounted on nozzle frame 20, thus imparts low-speed high-torque rotation to the nozzle frame 20 about the water pipe shaft 16, through engagement of pinion 31 with the gear track 32 rigidly mounted on the stationary frame 20.

The speed of the rotary movement of the nozzle frame is controlled solely by the water passing through the branch pipe 60, irrespective of the quantity of water which is directed through the water pipe 16 for discharge through flexible pipe 40 and the nozzle 67 which is detachably connected to the free end of this flexible portion 40. A support for this free portion of the nozzle 40 is provided by the bifurcated frame 41 having arms 42 and 42' pivotally connected to the lateral walls of the U-shaped nozzle frame 21 at pivots 48 and 48'. The head of the frame 41 supports the free end of hose 40, and the mouth 41' thereof terminates in a threaded end for attachment thereto of nozzle 67. The bifurcated frame 41 also has mounted thereon at pivots 46 and 46' a pair of levers 44, 44' across which is bridged a rigid arm 45 carrying at the mid-portion thereof a follower or guide roller 50, which preferably is mounted on ball-bearings, and which is designed to roll over the trackway 51 formed on the upper edge of the cylindrical frame 10. Additional levers 43 and 43' extend between the free ends of arm 45 and pivots 47 and 47' on the lateral walls of the nozzle frame 21, forming a compound leverage system of 2 to 1 advantage. Opening movements of the sets of levers 43, 44 and 43', 44' caused by upward movements of roller 50 result in corresponding double displacements between the pivots 47, 47' and 46, 46', respectively.

As shown in Fig. 4, the trackway 51 is provided with four equally spaced rises 51a and low points 51b, with the rises and descents from the points 51a being comparatively steep. These rises effect the maximum inclinations 70 of the nozzle in order to have the water reach the corners of the square to be watered, as shown in Fig. 5. The nozzle drops from the high points 40 to a smaller inclination designated as 71 to water the sides of the square area to be watered.

By means of the system of compound levers described above, which in effect functions as a pantographic arrangement of toggle levers, comparatively small vertical movements of the roller 50 on the cam track 51 are multiplied to give correspondingly larger angular movements of the nozzle head 41, so that in effect the nozzle can be varied from an inclination of approximately 15° to water the sides of a square to a maximum angle of approximately 45° which has been found desirable in order to reach the corners of the area to be watered.

While the detachable nozzle 67 is shown with an arcuate lower surface 68, which is provided with a plurality of perforations, the nozzle construction can assume different forms.

The invention lends itself to many variations. For example, the cam track for guiding the control roller for the nozzle may be formed on a separate annulus which may be detachably mounted on the supporting casing 10. A plurality of such may be provided for purposes of interchangeability in conformity with different pattern effects. Rectangular areas may be watered by arranging the four rises 51a at pairs of spaced points other than 90° apart. Furthermore, polygons of any number of sides may be watered by forming a cam track with a corresponding number of rises.

The size of the area being sprinkled may be controlled by varying the pressure of the main water supply by a valve at the source of water or at the sprinkler; a decrease of the main water supply results in a reduction of the size of the

sprinkled area while an increase of water results in an enlargement of the area.

The water issuing from jet pipe 60 scatters in the vicinity of the sprinkler after the energy therein spends itself in striking the blades 62 of the water wheel.

While I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claims.

I claim:

1. A rotary sprinkler comprising a stationary cylindrical support, a nozzle frame rotatably mounted in said support and terminating in a tilttable nozzle outlet, a water supply conduit connected to the inlet of said nozzle frame, a water-wheel mounted for positive rotation on said frame, a branch pipe connected to said supply conduit with the outlet end thereof directed towards said water-wheel for impinging the water diverted therethrough against said water-wheel, reduction gearing between said water wheel and support for imparting rotation to said nozzle frame at low speed and high torque, and a circular trackway formed on the upper edge of said cylindrical support having alternate rises and depressions therein and supporting part of said nozzle frame for cyclically varying the inclination of the tilttable nozzle outlet in the course of its rotation.

2. A rotary sprinkler comprising a stationary support, a nozzle frame rotatably mounted in said support and terminating in a tilttable nozzle outlet, a water supply conduit connected to the inlet of said nozzle frame, a water-wheel mounted for rotation on said nozzle frame on a vertical axis displaced from the vertical axis of rotation of said nozzle frame, a branch pipe connected to said supply conduit with the outlet end thereof directed towards said water-wheel for impinging the water diverted therethrough against said water-wheel, reduction gearing between said water-wheel and support for imparting positive rotation to said nozzle frame at low speed and high torque, a circular trackway on said support having alternate rises and depressions, and a guide roller in contact with said trackway and connected with said tilttable nozzle for cyclically varying the inclination of said nozzle in the course of its rotation.

3. A rotary sprinkler as set forth in claim 2 wherein said last-mentioned guide roller is connected to said tilttable nozzle through a compound lever system which amplifies the movements of said roller in the transmission thereof to said tilttable nozzle.

4. A rotary sprinkler comprising a stationary cylindrical support, a water supply pipe extending upwardly within said support along the central axis thereof, a nozzle frame rotatably mounted on said pipe with a flexible portion extending upwardly therefrom, a vertical rotary shaft mounted on said nozzle frame having a water-wheel at the upper end thereof and a worm spiral at the lower end thereof, a transverse shaft extending from said nozzle frame adjacent to the lower end thereof, a sleeve rotatably mounted on said transverse shaft having at one end thereof a large worm-wheel in mesh with said worm spiral and a small gear wheel at the opposite end thereof, a ring mounted on the inside of said

stationary cylindrical support having a circular gear track for guiding said last-mentioned gear wheel, a branch pipe connected to said nozzle frame for diverting a portion of the water therefrom and directing it against said water-wheel for imparting rotation thereto and to said nozzle frame through the intermediary of said gearing, a cam track having alternate rises and depressions at the upper end of said stationary cylindrical support, and a follower adapted to ride on said cam track and connected to said flexible portion of said nozzle frame for cyclically varying the inclination of said portion in the course of rotation of said nozzle frame.

5. A rotary sprinkler comprising a stationary cylindrical support, a water supply pipe extending upwardly within said frame along the central axis thereof, a nozzle frame rotatably mounted on said pipe with a flexible portion extending upwardly therefrom and terminating in a perforated discharge nozzle, a vertical rotary shaft mounted on said nozzle frame having a water-wheel at the upper end thereof and a worm spiral at the lower end thereof, a transverse shaft extending from said nozzle frame adjacent to the lower end thereof, a sleeve rotatably mounted on said transverse shaft having at one end thereof a large worm-wheel in mesh with said worm spiral and a small gear wheel at the opposite end thereof, a ring mounted on the inside of said stationary cylindrical frame having a circular gear track for said last-mentioned gear wheel, a branch pipe of small cross-sectional area connected to said nozzle frame for diverting a portion of the water therefrom and directing it against said water-wheel for imparting rotation thereto and to said nozzle frame through the intermediary of said gearing, a cam track having alternate rises and depressions formed on the top edge of said stationary cylindrical support, and a guide roller adapted to ride on said cam track and connected to said flexible portion of said nozzle frame for cyclically varying the inclination of said discharge nozzle in the course of rotation of said nozzle frame.

6. A rotary sprinkler as set forth in claim 5 wherein the cam track is formed with four sharp rises with intervening depressions spaced 90° apart to effect the watering of a square area.

7. A rotary sprinkler as set forth in claim 5 wherein said branch pipe is provided with a throttling valve to control the speed of the water-wheel and consequently the speed of rotary movement of said sprinkler.

8. A rotary sprinkler as set forth in claim 5 wherein said last-mentioned guide roller is connected to the nozzle frame through the intermediary of toggle levers which amplify the movement of the guide roller which are imparted to the nozzle frame.
